UNITED STATES PATENT OFFICE.

LIBBY P. RICHARD, OF LYNN, MASSACHUSETTS.

DESIGN FOR A HAT AND UMBRELLA RACK.

SPECIFICATION forming part of Design No. 32,834, dated June 12, 1900.

Application filed April 18, 1900. Serial No. 13,399. Term of patent 7 years.

To all whom it may concern:

Be it known that I, LIBBY P. RICHARD, a citizen of the United States, and a resident of Lynn, county of Essex, and State of Massachusetts, have invented and produced a new and original Design for Hat and Umbrella Racks, of which the following is a specification, reference being made to the accompanying drawings, forming a part thereof, in to which—

As shown in the drawings, the leading and material features of my design consist of a single piece of wire which is bent to form a vertically-arranged portion a, which is curved in semicircular form, and a curved or yoke-shaped horizontal portion b. Both ends of the wire are bent to form screw-eyes c d, and it is bent downwardly to form a loop or screw-eye e midway between the curved portions a and b. From the ends of the curved portion a the wire extends horizontally in the plane of said curved portion and then is bent at a sharp angle and extends to the eye d at one end and to the eye e at the other end, as shown.

The device is designed to be secured to any suitable support by simply passing screws through the various screw-eyes above described.

The manner of using the hat-rack is as follows: The hat will be placed with the rim inside of the horizontally-bent portions, so that the bottom side of the rim will be next the support and the crown will rest in the curved portion a and will extend outwardly from the support. The manner of use of the umbrella-rack will be obvious.

Having described my invention, what I claim as new, and desire to secure by Letters Patent of the United States, is as follows:

The design for a hat and umbrella rack, as herein shown and described.

In testimony whereof I sign my name in the presence of two witnesses.

LIBBY P. RICHARD.
